United States Patent Office

Des. 201,524
Patented June 29, 1965

201,524

PHONOGRAPH OR THE LIKE

Frank M. Grunwald, Syracuse, N.Y., assignor to General
Electric Company, a corporation of New York

Filed Sept. 18, 1963, Ser. No. 76,624

Term of patent 14 years

(Cl. D56—4)

FIG.1

FIG.2

FIG.3

FIGURE 1 is a frontal perspective of a phonograph embodying one form of this design invention, with the door closed;

FIGURE 2 is a frontal perspective view of the phonograph of FIG. 1 with the record changer in its operative position;

FIGURE 3 is a plan view of the phonograph of FIGURE 1;

FIGURE 4 is a right end view of the phonograph as shown in FIGURE 1;

FIGURE 5 is a right end view of the phonograph for the record changer position shown in FIGURE 2;

FIGURE 6 is a left end view of the phonograph as shown in FIGURE 1.

FIGURE 7 is a left end view of the phonograph for the record changer position shown in FIGURE 2;

FIGURE 8 is a rear view of the phonograph in FIGURES 1 and 2;

FIGURE 9 is a view similar to FIGURE 1 but showing another embodiment of my new design wherein the speakers are covered by louvered front wall portions.

I claim:

The ornamental design for a phonograph or the like, substantially as shown.
